UNITED STATES PATENT OFFICE.

HERMAN G. PAPE, OF NEW YORK, N. Y.

SPEAKING AND SIGNALING APPARATUS.

1,272,993.

Specification of Letters Patent. Patented July 16, 1918.

Application filed December 26, 1914. Serial No. 879,0

To all whom it may concern:

Be it known that I, HERMAN G. PAPE, a citizen of the United States, and resident of New York, in the county of New York and State of New York, have invented certain new and useful Speaking and Signaling Apparatus, of which the following is a specification.

My invention relates to speaking and signaling apparatus adapted for use in closed body vehicles such as limousines, taxicabs, etc., to enable the occupant or passenger to signal to the driver or chauffeur and then convey a message telephonically, and whereby the driver or chauffeur may respond by speaking directly to the passenger through a suitable sound conveying and amplifying means. The apparatus may also be used to enable conversation or the transmission of messages between persons in adjoining rooms or in other situations where persons only a short distance apart, are separated by a wall or other obstacle whereby some special apparatus is required for verbal communication.

This invention is a modification of that disclosed in my Patent No. 1,060,851, May 6, 1913, and is adapted for the same general purposes therein set forth.

An object of the invention is to provide an improved form of automatic signal device associated with the telephone transmitter whereby when the transmitter is picked up a signal is automatically transmitted to attract the attention of the driver or person to whom a message is to be transmitted. The invention further provides means to automatically establish the speaking circuit by lifting the transmitter from its pocket or other keeper or other support, and again break the circuit by restoring the transmitter to its keeper or support.

Another object of the invention is to provide in a telephone circuit, a microphone hand set carrying a current switch, operable by hand to make and break the circuit for signaling purposes, the switch also being automatically operated to make the circuit when the hand set is removed from its support, and operated to break the circuit by the act of restoring the hand set to its support.

Other features and advantages will appear hereinafter.

55 In the accompanying drawings, Figure 1

is a view showing diagrammatically an arrangement of apparatus embodying the principles of my invention, the speaking tube and sound amplifying and reechoing devices being shown partly in section. Fig. 2 is a 60 part sectional view of the transmitter and its pocket. Fig. 3 is a part sectional plan view of the speaking tube and the sound amplifying and reechoing means. Fig. 4 is a sectional view as indicated by the section line 4—4 on Fig. 3. Fig. 5 shows a modification in which the automatic switch is separate from the transmitter but arranged to be operated by removing or restoring the transmitter from or to its support. 70

When the apparatus is used as a telephone signal system for a closed vehicle, the passenger or occupant of the closed compartment withdraws the transmitter 1 from the pocket 2 when he desires to communicate with the driver and may talk into the transmitter, the sound being telephonically transmitted to the receiver 3 where the sound is reproduced, said receiver located within a sound reechoing bell 4, which is preferably located close to the driver or chauffeur. The bell 4 is connected through a speaking tube 5 extending through the wall of the vehicle, with a sound amplifying and reechoing bell 6. The driver may speak into the bell 4, the sound being conveyed directly into and through the tube 5 and amplified within the bell 6, so that it is distinctly heard by the occupant in the closed compartment. The telephone receiver 3 may be of any approved construction and as diagrammatically shown in Fig. 1, comprises a magnet coil 7 wound on a magnet core 8, the magnetic impulses setting up corresponding vibrations in an iron diaphragm 8' within the casing 3'. The conductors leading to the coil 7 extend through terminal openings 9 in the casing. The sound waves set up by the diaphragm are directed through an amplifier 10 which may be in the form of a flared tube or funnel having a screw threaded connection with a teat or projection 11 of the casing 3'. The sound conveyed from the amplifier 10 through the tube 5 strikes against a concave deflector 12 which is secured as by means of brackets 13 and screws 14 within the bell 6. The sounds reflected from the deflector 12 strike the reflecting surface 15 of the reechoing chamber or bell 6 and are directed outwardly through the annular passage 16 80

85 90 95 100 105 110

The sound waves set up by the diaphragm are directed through an amplifier 10 which may be in the form of a flared tube or funnel having a screw threaded connection with a teat or projection 11 of the casing 3'. The sound conveyed from the amplifier 10 through the tube 5 strikes against a concave deflector 12 which is secured as by means of brackets 13 and screws 14 within the bell 6. The sounds reflected from the deflector 12 strike the reflecting surface 15 of the reechoing chamber or bell 6 and are directed outwardly through the annular passage 16 110

between the deflector 12 and the wall of the bell 6.

The occupant of the vehicle may speak directly into the bell 6, the direction of the sound being reversed, that is the sound striking the surface 15 is reechoed on the surface 12 and transmitted through the tube 5, and passes outward through the annular passages formed by the wall of the bell and 10 the rolled end of the funnel 10 and the casing 3'.

The casing 3' may be secured centrally within the bell by screws 17 extending through the bell and threaded into bracket 15 arms 18 projecting from the casing.

The speaking tube 5 is preferably a flexible metal tube permitting the bells at each end of the tube to be moved or placed in any convenient position and facing in any direction. Each of the bells also has a swivel connection with the tube thereby increasing the flexibility of the apparatus. The union between the bell 4 and the tube 5 comprises a sleeve 20 threaded into an opening in the base of the bell 4. An outer sleeve 21 threaded on to the sleeve 20 is provided at its outer end with an annular recess to receive an inturned flange on the adjoining end of a coupling ring or collar 23, in 25 which is secured by soldering, brazing or otherwise, the end of the tube 5. As the sleeve 21 swivels in the collar 23, the bell 4 may be rotated relatively to the tube 5, and owing to the eccentric connection of the bell 35 with the tube a wide range of adjustment of the bell is provided.

The connection between the tube 5 and the bell 6 is similar to that just described and comprises an inner tube 24 threaded within 40 the bell 6, and outer sleeves or rings 25 and 26 connected respectively to the tube 24 and the tube 5 and swivelly connected with each other at 27. The sleeve 24 is extended within the bell 6 to form a support for an amplifying horn 28, the end of which is rolled or turned back to form a sound deflector. The end 30 of the tube 24 is preferably tapered to conform to the tapering end of the horn 28.

50 The microphone transmitter as diagrammatically shown in Fig. 1 may comprise a diaphragm 31 responsive to sound vibrations impressed thereon and operable in a well known manner on the resistance varying medium 32 between the diaphragm and electrode 33 to vary the resistance in the electrical circuit and thereby set up electrical impulses which in the reproducer 3 are transformed into sound waves. The diaphragm 31 is electrically connected through a spring arm 34, switch contacts 35 and a spring arm 36 to a terminal socket 37. The electrode 33 is connected through a conductor 38 to a socket 39. Split pin cord terminals 40 and 41 are adapted to fit in the

sockets 37 and 39 respectively and are connected to the ends of conductors preferably in the form of a flexible cord 42 extending to a cord outlet block 43 which may be of any approved form. The block 43 may be 70 secured in any convenient position to a wall or other part of the vehicle.

A feature of the present invention relates to means for giving a signal by the removal of the transmitter 1 from its casing, keeper or support 2. Such means comprises an automatic circuit opener or closer 44 within the transmitter which when the transmitter is placed in the pocket 2 is automatically forced inward against the tension of the spring arm 36 separating the latter from the arm 34 and another spring arm 45 which carries a contact 46 adapted to electrically connect with the arm 36 momentarily when the push button 44 is released. The operation of the signal device is as follows:—When the moving contact of the circuit opener or closer is released by the withdrawal of the transmitter from its pocket or keeper, the arm 36 springs downward 90 (Fig. 1), moving the button 44 outward. During this movement, the arm 36 first strikes the contact 46 on the arm 45 thereby establishing a signal circuit. This circuit may be traced from the terminal 47 of the battery B through conductor 48, bar 49 of the terminal block 50, conductor 51, magnet coil 7, conductor 52, bar 53, conductor 54, cord 42, contacts 41, 39, conductor 55, resistance 56, switch arm 45, contact 46, switch arm 36, contacts 37, 40, cord 42, wire 57, bar 58 and conductor 59 to the opposite terminal 60 of the battery. The circuit thus established permits a momentary flow of current which sets up a magnetic impulse in 105 the magnet 8, and produces a momentary vibration of the diaphragm which is heard as a sharp sound or click which serves as a signal to direct the attention of the driver. The circuit thus momentarily established is 110 immediately broken as the continued downward movement of the switch arm 36 brings the outer end of said arm against an insulating piece 61 and forces the arm 45 downward and opens the circuit at the contact 46. The 115 arm 36 now engages the contact 35 on the arm 34 and establishes a speaking circuit which it is impossible to break through any ordinary jar of the carriage or the passenger within. The resistance 56 prevents 120 an excessive current and may be adjusted to secure as powerful an action of the magnet 7 as the adjustment of the diaphragm 8' will permit without causing the diaphragm to strike and stick to the magnet. 125 The speaking circuit is the same as the signal circuit already traced except that within the transmitter the circuit is by way of the conductor 38, electrode 33, resistance 32, electrode 31 and switch arms 34, 36. 130

It will be seen from the above that the picking up of the transmitter operates automatically, first to give a signal, and then to establish the speaking circuit, the speaking 5 circuit being maintained without the need of the speaker holding a switch button depressed, or otherwise maintaining the circuit. The return of the transmitter to its keeper which has its opening limited to 10 cause a fairly firm grip on the transmitter, automatically reopens the circuit by pressing the button 44 inward.

It will also be apparent that it is not necessary, after the removal of the transmitter from its support, to restore the same 15 and then again remove it, in order to give a signal; since, when once the hand set is in the operator's hand for use, the switch is quite readily operated by hand, as by the 20 pressing of the protruding button.

The transmitter 1 may comprise an inclosing casing 63 and a handle 64 through which the cord 42 extends, said handle having an extension 65 forming a backing for the casing 63. The handle is also provided with a pocket or chamber 66 to accommodate the split pin terminals 40 and 41, and socket terminals 37 and 39 (Fig. 1).

The terminal clips 47, 60, on the battery, 30 and on the bars 49, 53, 58, may all be of like construction and each comprises a spring arm 66' with an opening to receive the elbow of an arm 67 so that by springing the arm 66' inward, an opening is provided between the two arms to receive a wire terminal and securely clamp it when the arm 66' is released. It will be seen that all the electrical connections required in installing the apparatus in a vehicle or other situation can 35 be readily made without the use of special tools, the ripping up of covered, embedded, or tacked down wires or cords and thereby perhaps the spoiling of fancy trimmings or furnishings such as are commonly used in 40 expensive limousines, or the like.

Fig. 5 illustrates a modification in which the automatic switch for the signal circuit and speaking circuit is separate from the transmitter 1', and operated as in Fig. 1 by the removal and replacing of the transmitter. In this arrangement the transmitter 1' when placed in the pocket 2', presses a spring actuated arm 70 and moves the switch arm 36' to open position. When the transmitter is withdrawn, the switch arm 36' springs to the right, momentarily closing the signal circuit as it reaches the intermediate position shown in this figure, and then closes the speaking circuit. The portion of the speaking circuit between the conductors 57' and 54' may be traced from conductor 57' through switch arms 36', 34', connector block 43, cord 42, transmitter 1', cord 42, connector block 43 and wire 54'.

65 Various modifications may be resorted

to without departing from the spirit and scope of my invention, and some parts of the invention may be used without others.

What I claim as new and desire to secure by Letters Patent of the United States is:—

1. In a telephone system, in combination, a telephone circuit, a microphone hand set in said circuit, a support for the hand set, an exterior pressure operated current switch carried by the hand set, said switch being 75 operable by the hand of the operator to make and break the circuit for signaling purposes, and operable by the removal of the hand set from the support, to make the circuit, and also operable by the restoring of 80 the hand set to the support, to break the circuit.

2. The combination with a telephone transmitter, of a fixed resistance carried by the transmitter or its support, a voice reproducer, electrical circuit connections, means operable automatically by the removal of the transmitter from its support to send a current through the resistance and the reproducer, then to shut said current off and 90 then to establish its flow through the transmitter and reproducer with the resistance out of the circuit.

3. The combination of a microphone, a receiver, a fixed resistance, a source of current supply, means to transmit current from said source of current supply automatically and selectively through the fixed resistance and the receiver and thereafter with the fixed resistance out of the circuit through 100 the varying resistance of the microphone and the receiver.

4. In a telephone system, a signal circuit comprising a fixed nonmagnetic resistance, a speaking circuit, a transmitter and sound 105 reproducer in said circuit, said fixed resistance permitting the passage of a greater flow of current than the varying resistance of the transmitter before the latter is spoken into, and switching means for permitting 110 the alternate flow of current through the signaling circuit and through the speaking circuit, the fixed resistance being always out of circuit while the transmitter is in circuit and serving the exclusive purpose of 115 limiting the current flow for signaling purposes.

5. In a telephone system for vehicles, a microphone hand transmitter, a switch carried thereby, a pressure controlling means by 120 which the switch is operated, a reproducer for the transmitter at a point remote therefrom, a gripping pocket or keeping member for the transmitter having a limited opening for compressing the pressure-controlling 125 means, said switch being in a closed circuit position when the transmitter is removed from its pocket or keeping member, and said switch being open when the pressure controlling means is gripped or compressed by 130

the positioning of the transmitter to its pocket or keeping member.

6. In a phone system for vehicles, a microphone hand transmitter, a reproducer for the same at a point remote therefrom, a gripping pocket or keeper having a limited opening for the transmitter, and a switch having a resilient member, said resilient member being compressed for holding the switch contacts open when the transmitter is stored in its pocket or keeper and springing into contact position with the removal of the transmitter from its pocket or keeper.

7. In a telephone system, the combination with a telephone circuit, of a removable hand transmitter therein, a gripping support by which said transmitter is carried, a receiver comprising a signal device in the circuit remote from the transmitter, a circuit closer, and pressure controlled means actuated by the removal of the transmitter from its support to close said circuit closer and cause said signal device to give a signal or notice of a message about to be given and then to establish a speaking circuit for the transmitter.

8. In a telephone system, the combination with a telephone circuit, of a hand instrument in said circuit comprising sound transforming mechanism, an inclosing casing, a handle therefor, a telephone receiver comprising a signal device in said circuit at a point remote from the said instrument, and a switch comprising a push button projecting from the casing and operable when unrestrained to establish an electrical circuit for said mechanism, and operable when external pressure is applied to said button to cause an electrical impulse to be given to said signal device and also to open said circuit.

9. In a telephone system, a telephone circuit, a hand telephone comprising electro-responsive sound transforming mechanism in said circuit, a normally open shunt circuit across said transforming mechanism, means to automatically establish a circuit through said shunt and through said mechanism when external pressure on the said hand telephone is removed by removing the telephone from its support and to open the circuits when pressure is applied by restoring the telephone to its container or support, and a telephone receiver comprising a signal device in said circuit controlled by said switch.

10. In a telephone system, the combination of a microphone hand set, a support therefor, an exterior pressure operated current switch carried by the hand set, said

switch being operable by the removal of the hand set from its support, to make circuit connections for a signalling circuit and other connections for a speaking circuit, said switch also operable by the restoring of the hand set to the support, to break the circuit.

11. In a telephone system, the combination of a microphone hand set, a support therefor, an exterior pressure operated current switch carried by the hand set, said switch being operable by the removal of the hand set from its support, to make circuit connections for a signalling and speaking circuit, said switch being also operable by the restoring of the hand set to its support, to break circuit.

12. In a telephone system, the combination with a telephone circuit, of a hand instrument in said circuit, a signal device in said circuit at a point remote from said hand instrument, a fixed resistance, a source of current supply, a switch comprising a push member operable when released from an external pressure to establish an electrical circuit through said fixed resistance and through said signal device, then to open the circuit, and then to establish an electrical circuit through the hand instrument and through the signal device with said resistance out of the circuit, said switch being also operable when external pressure is applied to said push member to cause the breaking of the circuit through the hand instrument, then to establish a circuit through the fixed resistance and through the signal, and then to break said latter circuit.

13. In a telephone system, the combination with a telephone circuit, of a hand instrument in said circuit, a signal device in said circuit at a point remote from said hand instrument, a fixed resistance, a source of current supply, a switch comprising a push member projecting from said hand instrument and operable when released from an external pressure to establish an electrical circuit through said hand instrument, and operable when external pressure is applied to said push member, to break the circuit through said hand instrument, then to establish the circuit through said resistance and through said signal device, and then also to open said circuit.

Signed at New York, in the county of New York and State of New York this 21st day of December, A. D. 1914.
